UNITED STATES PATENT OFFICE.

JAMES A. HORTON, OF PROVIDENCE, RHODE ISLAND, ASSIGNOR TO
IROQUOIS MACHINE COMPANY, OF NEW YORK, N. Y., A CORPO-
RATION OF NEW YORK.

WIRE-DRAWING MACHINE.

SPECIFICATION forming part of Letters Patent No. 742,987, dated November 3, 1903.

Application filed November 20, 1902. Serial No. 132,072. (No model.)

To all whom it may concern:

Be it known that I, JAMES A. HORTON, of Providence, in the county of Providence and State of Rhode Island, have invented certain new and useful Improvements in Wire-Drawing Machines, of which the following is a specification.

This invention has for its object to provide a practical system for drawing wire continuously or in one operation through a series of dies whereby its diameter is reduced by stages and its length correspondingly increased. The usual method of drawing wire is to pass it through a single die and wind it upon a drawing-drum or "block." Then if its diameter is to be further reduced it is removed from the drawing-drum, put onto a reel, and subjected to a repetition of the above process with the use of a smaller die. Each successive operation or "pass" therefore requires the rehandling of the wire and the consumption of considerable time and labor. The continuous process whereby the wire passes through several dies in a series and around a traction-drum between each pair of dies, which drum the wire encircles after the manner of a rope around a windlass-drum, whereby the wire is given its whole or a very considerable reduction in one continuous operation, would effect a considerable saving in time and labor, but has not come into as general use as would otherwise follow if the following difficulties could be avoided. In each passage through one of the dies of the continuous series the wire receives a certain elongation, depending upon the relation between the diameter of the wire before it passes through the die and the diameter of the hole in the die, and the next succeeding traction-drum around which the wire passes must have a peripheral speed corresponding to the linear speed of the wire, or, stated in other words, the peripheral speed of the drum succeeding the die must exceed that of the drum preceding the die by an amount equal to the elongation of the wire in the die. All the successive traction-drums must therefore have different speeds, which in practice are figured to be slightly faster than the correct speed with perfect dies and material; but it

has been found impossible to keep these relative speeds regulated absolutely, because of changes in the diameter of the holes in the dies due to wear and because of variation in the stock. It is common therefore in these continuous-pass machines for the traction-drums to be going very much faster than the wire. This has the same effect as in a windlass where the leading-off rope is slackened—that is to say, the coil of wire around the drum loosens, and the drum rotates within the coil. Not only does this have an effect of producing great inequalities in the distribution of strains on the wire, resulting in frequent breakages thereof, but the abrasion of the wire by the rotation of the drum within its wrap wears off small particles, which are liable to collect in the die and distort or scratch the same or decrease the diameter of the wire. More particularly, however, the movement of the drum will wear off the protecting or lubricating coating of the wire. This is particularly objectionable in drawing steel wire. Steel wire before it is drawn is treated with a thin coating, which is whitewash in the larger sizes and copper or soft-metal plating in the smaller sizes, for the purpose of preventing contact between the die and the body of the wire. If a naked steel wire is drawn through a die, which, except in the smaller sizes, is made out of steel, the steel wire coming in contact with the steel of the die will quickly spoil the die. It has been found in practice that this objection can be largely, if not entirely, avoided by coating the steel wire with a protecting-coating. Many different kinds of compounds are employed for this purpose; but they all substantially depend upon the principle of preventing direct contact between the steel of the wire and the die. It has been further found that with a proper working apparatus one coating is sufficient for a large number of drawing actions through single dies, but that in the continuous process the friction between the intermediate drums rubs off and destroys this coating, and hence interferes with the proper repeated reduction in the series of dies. To overcome this difficulty, the intermediate or traction

drums are made as follows: Each of the drums consists of a wire-forwarding means and a driving mechanism having an automatically regulating or compensating connection with 5 said means, whereby the slippage between the engaging means and the wire is substantially avoided and whereby the slippage necessary to regulate or compensate for the variance in the diameter of the dies and the 10 inequalities in the material or other causes takes place between the wire-forwarding means and the driving mechanism. This automatic regulation or compensation is measured or determined by the call of the 15 wire beyond the particular intermediate drum or by the tension of the wire. The driving mechanism is preferably run at a constant speed slightly in excess of the proper speed. In this way abrasion of the wire is avoided.

20 In carrying my invention into practice in the way now best known to me I make the connection between the wire-forwarding means and the driving mechanism a friction connection, the pressure in which is automatically regulated by the tension of the wire. In the specific construction the wire-forwarding means consists of a number of segments or shoes collectively having a face or surface which engages and forwards the 25 wire. These shoes are mounted on a revolving hub actuated by suitable gearing, which hub and its gearing constitute the driving mechanism for the wire-forwarding means. The wire is wrapped or given one or more 30 turns around the wire-forwarding means, whereby the frictional engagement or connection between the wire-forwarding means and the driving mechanism is automatically regulated by the tension of the wire.

35 My invention also consists in the drum as an improved feature, which, although I have not shown it, can be embodied in a single-drum machine, a number of which may be used in series with certain of the results attained by the multiple machine hereinafter 40 described.

45 Of the accompanying drawings, Figure 1 represents a plan view of a wire-drawing machine constructed in accordance with my invention. Fig. 2 represents a side elevation thereof. Fig. 3 represents an axial vertical section. Fig. 4 represents a section on line 44 of Fig. 3. Fig. 5 represents a section on line 55 of Fig. 4. Fig. 6 represents a section 50 on line 66 of Fig. 3. Fig. 7 represents a plan view of one of the idle friction-wheels. Fig. 8 represents a side elevation thereof. Fig. 9 represents a section on line 99 of Fig. 8. Fig. 10 represents a vertical section of one of 55 the traction-drums on an enlarged scale. Fig. 11 represents a side elevation thereof. Fig. 12 represents a plan view of a portion of the annular wire-engaging device on one of the drums. Fig. 13 represents a section on line 65 1313 of Fig. 12. Fig. 14 represents a vertical section through the spindle of one of the driven friction-wheels. Fig. 15 represents a

section at right angles to Fig. 14. Fig. 16 represents a section on line 1616 of Fig. 14. Fig. 17 represents a section on line 1717 of Fig. 16. Fig. 18 represents a detail perspective view of the trunnioned portion of the sleeve surrounding the spindle. Fig. 19 represents a section on line 1919 of Fig. 15. Fig. 20 represents a section on line 2020 of Fig. 15. Fig. 21 represents a detail perspective view of a member at the head of the spindle. Fig. 22 represents an axial section of one of the receiving-drums.

The same reference characters indicate the 80 same parts in all the figures.

In the drawings, 30 is the machine-frame, of circular outline, in the center of which is journaled a vertical shaft 31, driven in any suitable manner. On said shaft is keyed a 85 driving friction-wheel 32, and around said shaft in an annular series are arranged vertical shafts or spindles 33, to the lower ends of which are keyed driven friction-wheels 34 and above these wheels toothed pinions 35. 90 Between the wheels 32 34 on horizontal spindles 36 are mounted intermediate friction wheels or rollers 37, with tractive surfaces composed of leather or other suitable material. By means of screws 38, fixed against 95 axial movement in bearings 39 on the frame and engaging nuts 40 on the outer ends of the spindles 36, the rollers 37 may be moved between the wheels 32 34 toward or away from the central shaft 31. Such movement of a roller 100 37 varies its radial position on the respective wheels 32 34 inversely, so that the speed at which the wheel 34 is driven from the wheel 32 through the roller 37 may be varied as desired, the speed of any wheel 34 being variable 105 independently of that of the other wheels 34. In order that any wheel 34 may be arrested by lifting it from its roller 37, I surround each shaft 33 with a sleeve 41, held from rotation by a pin 42. The sleeve has studs or trunnions 43 43, projecting into inclined slots 44 44 on a cam 45, adapted to be oscillated by a 110 handle 46. Such oscillation produces a vertical movement of the sleeve 41, which is transmitted to the shaft 33 by means of a nut 115 480, abutting the upper end of the sleeve and mounted on a screw-stud 49, said stud having a head 48 at its lower end connected with a head 470 on the shaft 33 by a pair of flanged half-collars 47 47. By means of the nut 480 120 the axial relation of the sleeve 41 and shaft 33 may be adjusted. 490 is an oil-duct traversing the bearing formed by the above-mentioned parts.

Alongside of the several shafts or spindles 125 33 are other vertical spindles or holders 50 50, having gears 51 51 keyed to their lower ends and meshing with the pinions 35. I have shown the machine equipped with nine spindles 33 and nine spindles 50, divided up 130 among three drawing units. On every third spindle 50 there is a wire receiving or storing drum 52, having a forked coupling member 53, engaged with a complementary coupling

member formed as a stud 54, projecting from the spindle 50, whereby the drum is removably supported on said spindle and caused to rotate therewith. On the other two spindles 50 of each drawing unit are mounted traction-drums 55, having forked members 56 engaged with the studs 54, whereby said drums are removably attached to and caused to rotate with the spindles. On the outer 5 rim of the frame 30 are mounted brackets 57, carrying spindles or holders 58, on which are mounted loosely-rotating delivering-reels 59, one for each drawing unit, from which the wire unwinds. From the delivery-reel 59 of 10 each unit the wire 60 passes through a drawing-die 61, fixed vertically in the frame 30, then takes one or more turns around one of the traction-drums 55, then passes through a second die 61, then takes one or more turns 15 around the next succeeding traction-drum 55, then passes through a third die 61, and is finally coiled up on the receiving-drum 52. The apertures of the dies are graded in diameter, each succeeding die being smaller 20 than the next preceding one, so that the diameter of the wire is reduced by stages in passing through the drawing unit and its length increased at each stage. To meet this increase in length, the second one of the traction-drums 55 in the series is speeded faster 25 than the first, and the receiving-drum 52 is speeded faster than the second traction-drum, the object being to have the peripheral speed of the drum correspond approximately, but 30 to be slightly in excess of the linear speed of the wire.

The traction-drums 55 are made up of separable upper and lower portions 62 63, screwed together and loosely confining between them a series of separate segments or 40 shoes 64 64, forming a sectional annular wire-engaging portion. These shoes on each drum are carried around by their frictional engagement with the annular seat 65 on the drum, 45 against which they reside, and the amount of this friction obviously depends upon the inward radial pressure exerted by the coils of wire engaging the shoes 64. This pressure in turn depends upon the tension of that portion 50 of the wire which leads off from the drum into the next succeeding die. If the linear speed of this portion of the wire is less than that of the periphery of the drum at a diameter equal to that of the wire-engaging surface 55 of the shoes, the coil will loosen and diminish the frictional contact of the shoes with their seat 65. This loosening of the wire will also diminish its own friction against the shoes; but the shoes will nevertheless follow the 60 wire and any slip which occurs will take place between the shoes and the drum rather than between the shoes and the wire, thus avoiding abrasion of the wire. This may be somewhat due to the fact that the line contact of the 65 wire-coils gives a better gripping action between the shoes and the wire than surface con-

tact gives between the shoes and the drum; but neglecting this and also neglecting any effect which centrifugal force may have in causing the shoes to cling to the wire it is evident that 70 with equal friction between the wire and the shoes and between the shoes and the drum the first friction—namely, the outer one—will be a force acting on a longer arm from the center of rotation than the arm on which 75 the inner friction acts. The outer friction therefore prevails over the inner friction and the shoes must follow the wire and slip against the drum when the wire and drum have different speeds. During such slippage 80 the drum does not lose its propelling effect on the wire, for it will propel the wire in proportion to the friction between the shoes and the drum. It will be observed that the segments or shoes 64 64 collectively constitute 85 a wire-forwarding means or sectional supplemental friction-driver adapted to slip circumferentially on said driving mechanism and having an automatically-regulating or compensating frictional connection with its 90 driving mechanism or drum 55, regulated by the "call" or demand of the wire for being drawn, or, in other words, regulated according to the tension of the wire. I have found that the shorter these segmental shoes are 95 made the smoother and more uniform will be their motion on the drum within their grasp and the longer they are the more jerky, spasmodic, or step by step will be their motion on the drum. If the wire-forwarding device 100 is made in a one-part ring cut open at one point only, and therefore resilient, the motion or travel of said ring on the drum would be step by step, spasmodic, or jerky in a marked degree, owing to the fact that when 105 the opening in the ring comes into position of the wire line from die to die the amount of friction between the ring and drum is much greater than when the open side is in a position in its rotation opposite or farthest removed 110 from the wire line. This jerky or spasmodic action is caused by the elasticity of the ring. When the ring has its open side in the wire line, a given tension on the wire will close the ring much tighter on the drum than when 115 the open side is farthest away from the wire line. This is due to the fact that the same tension of wire would have to contend with its own friction for the distance of half-way around the drum. This tightening and loosening 120 would take place once in each revolution of the wire-forwarding means and would cause a jerky or step-by-step motion and an intermittent strain on the wire. To avoid this, I use short shoes and a number of them 125 instead of an elastic ring. To limit the outward movement of the shoes and prevent their outward displacement by centrifugal force, I provide the portions 62 63 of the drum with shoulders 630, (see Fig. 10,) which project over the outer faces of the sections 64.

The several drums 52 and 55 are mounted

in a liquor trough or receptacle 66 of annular form and continuous around the frame 30, designed to contain a lubricating liquor in which I immerse the wire-engaging portions 5 of the drums 55, the holes or eyes in the dies, and the wire as it passes between the said drums and dies. Such immersion of the wire in its transit to the dies lubricates the shoes, the wire, and the dies and carries off the heat 10 created by the friction between wire and dies. This trough has a continuous outer channel 67, encircling the frame, and small circular inner portions 68, containing the drums 52 and 55 and connected by straight channels 15 69, in which the dies 61 are located. The trough portions 68 connect by short channels 70 with the channel 67. A supply of lubricating liquor is maintained through a pipe 700, having branches 701 in the portions of 20 the trough 66 occupied by the several drawing units and overflows into a lower trough 71 through removable overflow-pipes 72, placed in drainage-apertures in the floor of the channel 67 and of such a height as to maintain the liquor at the desired level to immerse the wire. I arrange the floor of the channel 67 at a lower level than the floors of the trough portions 68, so that any sediment in the liquor may collect at the bottom of the channel 67, 25 where the liquor is comparatively undisturbed by the rotation of the drawing-drums. This channel 67 may be flushed from time to time by temporarily removing the overflow-tubes 72. In order to allow the wire to run 30 dry onto the receiving-drums 52, it is necessary to dam off those portions of the trough 66 containing said receiving-drums, which may be done by means of removable dams 73 35 73, located in the channels 67 and 69, the dies 61 also acting as dams in the channels 69. The portions of the trough thus shut off are kept drained by the removal of their overflow-tubes 72.

The liquid lubricant presented as above described to the friction-surfaces of the drums 55 and shoes 64 insures a regular or continuous slip between the shoes and their seat whenever the conditions require such slip. I have found that if said surfaces are not lubricated the slip is liable to be intermittent or step by step, the surfaces alternately adhering to and releasing each other, so that the wire is subjected to varying strains. This objection is obviated by the production of means for lubricating the friction-surfaces. I believe myself to be the first to combine in a wire-drawing machine wire-forwarding means, a driving mechanism therefor, said forwarding means and driving mechanism 55 having friction-surfaces adapted to slip on each other, and means for lubricating said surfaces to insure a continuous slip as distinguished from a step-by-step or jerky slip. I do not, therefore, desire to limit myself to the described liquor-trough as the means for applying the lubricant, it being obvious that the lubricant may be applied to the said fric-

tion-surfaces by any other suitable means without departing from the spirit of my invention. The preferred lubricant is water 70 containing soap in solution.

With a machine constructed as above described I am enabled to subject a batch of wire to nine passes on the one machine without rearranging the dies. This could of 75 course be accomplished in one continuous process instead of three; but in so doing a loss of time would result, owing to the practical limitation as to the highest speed at which the wire can be passed through a die. 80 The average speed of a series of nine drums would be much lower than that of three series of three drums each. I accordingly take the wire from the receiving-spindle or holder of the unit through which it has been drawn and 85 place it in the next unit of the same or a similar machine, this being accomplished by removing the receiving-drum 52 bodily from its spindle or holder 50 and placing said drum on the delivery-spindle or holder 58 of the 90 next unit. The several receiving-drums and delivery-reels of the different units are made interchangeable on the spindles of the other units, so that any delivery-reel can be substituted for any receiving-drum, and vice 95 versa, whereby I avoid direct handling of the wire, which has a tendency to cause it to snarl. It is apparent also that by reason of the interchangeability of the receiving-drums 52 and traction-drums 55 on each other's 100 spindles or holders the number of drawing-drums to a unit may be varied. Thus if all of the spindles but one were to carry traction-drums 55, and that one a receiving-drum with the dies properly arranged, the whole 105 machine would be a single drawing unit of nine drums. Conversely with receiving-drums on each spindle the machine would contain nine single-pass units, the radial dies 610 being permissibly used in this case. 110

With this machine I am enabled to realize a much greater maximum linear speed of the wire than has heretofore been found practicable, thereby increasing production, and I also improve the quality of the wire and increase the life of the dies. 115

Various modifications may be made in the described structure of my apparatus without departing from the spirit of the invention.

I claim—

1. In a wire-drawing machine, a die, a drum, a wire-forwarding means adapted to slip circumferentially on said drum and frictionally driven at the speed required by the call or tension of the wire, and means whereby the friction-surfaces of the drum and the wire-forwarding means may be uniformly and continuously lubricated. 120

2. In a wire-drawing machine, a die, a wire-drawing drum, driven at a predetermined speed, a compressible wire-forwarding means composed of independent segmental shoes loosely encircling the drum and adapted to distribute uniformly around the drum the 125 130

- pressure caused by the call or tension of the wire, whereby evenness of speed in each rotation of the wire-forwarding means is insured.
5. 3. In a wire-drawing machine, a die, a wire-drawing drum, means for rotating the drum, a wire-forwarding means consisting of segmental shoes loosely mounted on said drum, and means for preventing outward displacement of the shoes, the shoes being independently movable inwardly to cause them to be frictionally driven by the drum according to the call or tension of the wire at any speed less than that of the drum.
15. 4. In a wire-drawing machine, a die, a drum, a wire-forwarding means adapted to slip circumferentially on the drum, and a liquid-holding receptacle formed to hold a body of lubricating liquid in position to immerse the friction-surfaces of the drum and the wire-forwarding means.
25. 5. In a wire-drawing machine, a substantially vertical drum-holder and a substantially vertical reel-holder, and a drum or reel device interchangeable on said holders, the drum-holder having a coupling member which is engageable with and detachable from a complementary coupling member on the drum or reel by a vertical movement of the latter.
30. 6. In a wire-drawing machine, a series of drawing units comprising delivering-reels and substantially vertical holders therefor, and receiving or storing drums and substantially vertical holders therefor, the reels and drums having coupling members while the drum-holders have complementary coupling members, the said reels and drums being respectively interchangeable on each other's holders.

7. In a wire-drawing machine, the combination of wire-drawing dies, a wire-drawing drum, mechanism for rotating said drum, wire-forwarding means adapted to slip on said drum, a wire receiving or storing drum, and mechanism for rotating the said storing-drum, said mechanism having provisions for rotating the storing-drum at a relatively low speed and for then increasing the speed of its rotation to a fixed limit.

8. In a wire-drawing machine, a die, one or more wire-drawing drums with means for driving the same, wire-forwarding means adapted to slip circumferentially on said drum, a wire-storing drum and means for driving the same, and means for adjusting the relative speed of the several drums to correspond with the elongation of the wire due to its reduction through the several dies.

9. In a wire-drawing machine, a fluid-receptacle having a drum-containing portion and a deeper sediment-collecting portion, the latter being provided with a drainage-aperture, and a removable overflow-tube in said aperture having its intake above the floor-level of said drum-containing portion.

10. In a wire-drawing machine, a fluid-receptacle, a series of wire-drawing drums therein, removable means to isolate a portion of said receptacle containing one of the drums, and means to drain said portion, whereby the drum in said portion may be run without lubrication.

In testimony whereof I have affixed my signature in presence of two witnesses.

JAMES A. HORTON.
